United States Patent Office

Des. 181,405
Patented Nov. 12, 1957

181,405

MAIL BOX

Raymond F. Buffington, Manhattan Beach, Calif.

Application August 16, 1956, Serial No. 42,629

Term of patent 14 years

(Cl. D74—9)

FIG. 1

FIG. 2

FIG. 3

I claim:

The ornamental design for a mail box, substantially as shown.
